UNITED STATES PATENT OFFICE.

EUGENE HIGGINS, OF JACKSON, MICHIGAN.

METHOD OF OPERATING OIL-ENGINES.

952,430.

Specification of Letters Patent. Patented Mar. 15, 1910.

Application filed February 4, 1909. Serial No. 475,995.

To all whom it may concern:

Be it known that I, EUGENE HIGGINS, a citizen of the United States of America, residing at Jackson, in the county of Jackson and State of Michigan, have invented certain new and useful Improvements in Methods of Operating Oil-Engines; and I do hereby declare the following to be a full, clear, and exact description of the invention, such as will enable others skilled in the art to which it appertains to make and use the same.

My invention relates to improvements in the method of operating oil engines and more particularly engines using heavy hydrocarbon oils, which are not easily vaporized or converted into combustible gas, and its object is to provide a process which will enable anyone to successfully operate such engines.

My improved method consists essentially of; first vaporizing the oil in a chamber separate from any mixture of air; next superheating this oil vapor to such temperature as will convert the same into a highly combustible gas and preferably above the ignition temperature, whereby it will immediately ignite when coming in contact with the air and in further minutely subdividing this highly heated vapor into numerous small jets whereby it is more intimately incorporated with the body of compressed air, as will more fully appear hereinafter, reference being had to the accompanying drawings, of 35 a device adapted to perform my improved process, whereby the said process will be better understood and illustrated, in which drawings:

Figure 1. is a longitudinal, vertical section of an engine adapted to operate my said process; Fig. 2 is a transverse vertical section of the same on the line 2—2 of Fig. 1.; Fig. 3. a vertical sectional detail on the line 3—3 of Fig. 1.; and, Fig. 4. an enlarged perspective of the vaporizing and superheating chamber.

Like numbers refer to like parts in all of the figures.

1 represents the cylinder; 2 the piston; 3 the combustion chamber; 9 the intake and 10 the exhaust of an internal combustion engine of any convenient construction; 4 is a vaporizing chamber within the combustion chamber and spaced apart therefrom. At 55 one side of the chamber 4 is an inlet opening 5 to permit any suitable heavy oil, prefer-

ably some hydrocarbon oil, such as kerosene to be injected into the vaporizing chamber by any convenient pump 6.

The forward end of this chamber is closed 60 by a thick wall having numerous small passages or openings 7 therethrough for the escape of the oil vapor and also for the purpose of superheating the same; these passages being of such length and diameter as 65 to effectually superheat the vapor preferably to above the combustion temperature, and also to prevent the passage of compressed air or flame therethrough. 8 is a chamber at the rear of the vaporizing chamber for the purpose of preliminarily heating of the device 70 in starting the engine, by application of a blow torch, or other convenient means.

In operating this device, the process performed is as follows: The oil is periodically 75 injected through the opening 5 by means of the pump 6 and the heat of the walls of the chamber 4 immediately vaporizes this oil and creates sufficient pressure in said chamber to prevent the compressed air taken into 80 the engine through the intake valve 9 from entering therein. The heat of the perforated front wall of this chamber is maintained by the combustion of the gases in the combustion chamber of the engine to 85 such a temperature as to insure heating the oil vapor to a high degree in passing through the small elongated openings therein. This temperature converts the vapor into a fixed gas of a highly combustible 90 nature and also to raise the temperature sufficient so that when the small jets of hot gas escape from these openings, they will immediately inflame and burn with an intense, clear, blue flame, thus consuming the 95 compressed air and highly heated gases without depositing any carbon, or reducing the full effectiveness of the combustion. The intake 9 and exhaust 10 being opened in the usual way, the products of combustion 100 are discharged and fresh air taken in and compressed in the combustion chamber preparatory to a reproduction of the operation.

What I claim is:

1. The method of preparing a combustible mixture for operating oil engines comprising compressing air only in the combustion chamber of the engine, intermittently injecting oil into a separate vaporizing chamber 105 within the combustion chamber of the engine and heated by the combustion therein, 110

superheating the oil vapor above the temperature in a separate superheater and discharging the superheated oil into the compressed air in numerous small jets.

5. 2. The method of operating an internal combustion engine comprising compressing air only within the working cylinder of the engine, intermittently injecting a vaporizable liquid fuel into a vaporizing chamber
- 10 within said cylinder, superheating the vapor of said fuel above the ignition temperature in a superheater also in said cylinder, and

discharging said vapor so heated into the compressed air in numerous small jets and heating the vaporizer and superheater by direct action of the combustion of the mixture of superheated vapor and compressed air in contact therewith.

In testimony whereof I affix my signature in presence of two witnesses.

EUGENE HIGGINS.
